US00D950920S

(12) **United States Design Patent** (10) Patent No.: **US D950,920 S**
Dunham (45) Date of Patent: **** May 10, 2022**

(54) **FOOTWEAR**

(71) Applicant: **Target Brands, Inc.**, Minneapolis, MN (US)

(72) Inventor: **Austyn Dunham**, Minneapolis, MN (US)

(73) Assignee: **Target Brands, Inc.**, Minneapolis, MN (US)

(**) Term: **15 Years**

(21) Appl. No.: **29/754,406**

(22) Filed: **Oct. 9, 2020**

(51) LOC (13) Cl. **02-04**
U.S. Cl.

USPC **D2/970**; D2/969; D2/910; D2/912

(57) **CLAIM**

The ornamental design for a footwear, as shown and described.

DESCRIPTION

FIG. 1 is a front, top and right side perspective view of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and,

FIG. 7 is a back, bottom and left side perspective view thereof.

The bold broken lines in the drawings show portions that represent stitching and are part of the claimed design. The non-bold broken lines in the drawings show portions that form no part of the claimed design.

1 Claim, 7 Drawing Sheets
